UNITED STATES PATENT OFFICE.

WILLIAM A. NEVILLE, OF KEWANEE, ILLINOIS.

FLOOR-LAYING JACK.

1,354,332.

Specification of Letters Patent. Patented Sept. 28, 1920.

Application filed April 24, 1919. Serial No. 292,386.

To all whom it may concern:

Be it known that I, WILLIAM A. NEVILLE, a citizen of the United States, residing at Kewanee, in the county of Henry and State 5 of Illinois, have invented certain new and useful Improvements in Floor-Laying Jacks; and I do declare the following to be a full, clear, and exact description of the invention, such as will enable others skilled in the art 10 to which it appertains to make and use the same.

This invention relates to floor-laying jacks.

One object of the invention is to provide 15 an exceedingly convenient and very effective device for pushing floor-boards into place and holding them while being nailed to the sills or sub-floor.

A further object is to provide a device of 20 this character in which a hand of an operator may be assisted by a foot in a thoroughly practical, convenient and comfortable manner, and in which the foot entirely relieves the hand after the floor-board is 25 pushed into position, so that both hands may be employed in the nailing operation.

Other objects and advantages may become 30 apparent to persons who read the following details of description in connection with the accompanying drawings, in which;

Figure 1 is a side elevation of the device, a portion of the handle bar being broken off, the device being shown in a position attained 35 during the operation of pressing the board into its final position on the sill or sub-floor.

Fig. 2 is a top plan view of the part of the device disclosed in Fig. 1, the pusher being shown in dotted lines, as well as in full lines, thereby disclosing the device in its 40 open and folded positions.

Fig. 3 is a view somewhat similar to Fig. 1 except that the device is shown in longitudinal vertical section.

Fig. 4 is a side elevation illustrating the 45 device in the position attained after the floor-board has been entirely pushed to its final position.

Referring to these drawings in detail, in 50 which similar reference characters correspond with similar parts throughout the several views, the device comprises a pusher 5, a sill-engaging member 6, a hand-lever 7, a bolt or pivot 8 and a rivet or securing member 9.

The pusher or member 5 is formed of a strip of metal which is bent at points spaced

from its middle portion, as indicated at 10, and its end portions 11 are apertured at 12 to receive the pivot 8, and the end portions 11 converging from the bent portion 10 to 60 the apertures through which the pivot 8 extends.

The sill-engaging member 6 is formed of a strip of metal which is bent adjacent its middle portion, as indicated at 13, and its 65 ends terminate in sill-engaging elements or points 14 which are turned laterally of the main body of the bar or sill-engaging member 6. Ends of the sill-engaging member preferably diverge from the rivet 9, as indicated in Fig. 2, and the portion between the apertures 15 (which receive the rivet 9) and the bent portions 13 provide a space whose width is substantially equal throughout its length, and in this space is disposed a branch 70 16 of the hand-lever 7. The rear end portion of the branch 16 is apertured at 17 to receive the pivot 8, and the member 7 is also apertured at 18 to receive the rivet 9. It will be seen, therefore, that the hand-lever 75 7 is readily united with the sill-engaging member 6 while the members 6 and 7 are pivotally united with the pusher 5. Branch 19 of the hand-lever constitutes a handle-bar 80 for actuating the member 6, and coacts with 85 the latter for actuating the pusher 5.

In view of the foregoing description, it will be seen that ample space is provided behind the bar 19 for permitting the foot of the operator to be placed over the pivot 8, 90 thereby obtaining a most effective and convenient position for the foot in actuating the device and holding it in its effective position while the hands are otherwise employed.

In employing the term "sill-engaging" 95 in connection with this device, the broadest definition of the word sill is intended, that is, it is intended to mean any horizontal supporting structure. Furthermore, it is not intended to limit this device to the use here- 100 in ascribed thereto.

What I claim is:

1. In a floor-laying jack, a floor-board pusher, and a rigid structure including a sill-engaging member having a sill-engaging element at one end and a pivot at its other end portion, said pusher being movably secured to said sill-engaging member by said pivot, said rigid structure also including a handle-bar which extends from the middle portion 105 of the sill-engaging member substantially at right angles to the common plane of said 110

5 pivot and sill-engaging element, whereby the foot of an operator can conveniently be pressed down on the pivotal connection to aid the hands of the operator in the laying of floor-boards, substantially as shown.

10 2. A floor-laying jack comprising a pusher, a bifurcated sill-engaging member, a handle-bar, and a pivot, said pusher and sill-engaging members being pivotally connected together by said pivot, said pusher being formed of a strip of metal bent at points spaced from its middle and having its end portions converging toward said pivot, said sill-engaging member being formed of a strip of metal bent at points adjacent to its middle and having its ends terminating in laterally turned sill-engaging points, said bent middle portion being disposed between the converging end portions 15 of said pusher at the pivotal connection of the pusher and sill-engaging member, said handle-bar having one end portion disposed between and secured to the furcations of said sill-engaging member.

20 3. In a floor-laying jack, a bifurcated sill-engaging member comprising sill-engaging points on its furcations and having an aperture therethrough adjacent to the junction of its furcations, an L-shaped hand-lever having an aperture through one of its branches, a bifurcated pusher having an aperture in each of its furcations, the said 25 sill-engaging member having its said junc-

30 tion disposed between the furcations of said pusher, a pivot extending through said apertures and thereby pivotally uniting said pusher with said sill-engaging member and also uniting the latter with said hand-lever, and means co-acting with said pivot for holding said hand-lever and sill-engaging member in rigid relation to one another.

35 4. A jack comprising a pusher, a sill-engaging member, a handle-bar, and means including a pivot for rigidly securing said handle-bar to said sill-engaging member, 40 said pusher and sill-engaging members being pivotally connected together by said pivot, said pusher being formed of a strip of metal bent at points spaced from its middle and having its end portions converging toward said pivot, said sill-engaging member being formed of a strip of metal bent at points adjacent to its middle and having its ends terminating in laterally turned sill-engaging points, said bent middle portion being disposed between the converging end portions of said pusher at the pivotal connection of the pusher and sill-engaging member.

45 5. In testimony whereof I have hereunto set my hand.

WILLIAM A. NEVILLE.
